UNITED STATES PATENT OFFICE

LAWRENCE S. SHELDRICK, OF DETROIT, MICHIGAN, ASSIGNOR TO FORD MOTOR COMPANY, OF DEARBORN, MICHIGAN, A CORPORATION OF DELAWARE

STARTING MOTOR SWITCH

Application filed March 12, 1930. Serial No. 435,066.

The object of my invention is to provide a starting motor switch of simple, durable, and inexpensive construction.

A further object of my invention is to provide a starting motor switch especially adapted for use with the automobile starting motors. In the ordinary automobile, the starting motor is supplied with current from a six volt battery, one terminal of the battery being grounded while the other terminal is connected with the starting motor switch which in turn connects with the starting motor. Due to the low voltage used, this current frequently runs as high as 200 amperes so that the starting motor switch must be able to operate under these severe conditions. If the ordinary knife type switch were used, it would be quite costly and further, would not be convenient for the driver to operate; while if a simple-non-sliding push type switch were used the switch points would soon become pitted due to the arcing.

I have provided a switch in which an initial sliding action is obtained over a rather small area which is increased to a larger area as the switch is further applied. The large area carries the current normally used to operate the starting motor, while at the same time the arc produced when the switch is broken is restricted to a relatively small area over which a limited sliding action occurs to thereby prevent pitting of the switch contacts. I have thus obtained the desirable features of the knife type switch together with the simplicity of the push type switch.

Still a further object of my invention is to provide a starting switch having a relatively simple and inexpensive equalizing link extending between the movable switch member and the switch applying member.

With these and other objects in view my invention consists in the arrangement, construction, and combination of the various parts of my improved device, as described in the specification, claimed in my claims, and illustrated in the accompanying drawings, in which:

Figure 1 shows a side elevation of a starting motor having my improved starting motor switch mounted thereon, the switch being

shown in section to better illustrate the construction.

Figure 2 shows a sectional view taken on the line 2-2 of Figure 1.

Figure 3 shows a diagrammatic view of the various positions assumed by the switch member before full engagement, and

Figure 4 shows the position assumed by the switch member when the switch is fully engaged.

Referring to the accompanying drawings, I have used the reference numeral 10 to indicate generally an automobile starting motor. This motor is generally secured to an engine fly wheel housing in position forwardly and beneath the front floor boards of the automobile. A terminal is secured in the upper body of the starting motor 10 and is insulated therefrom by means of insulation 12. A head 13 is formed on the outer end of this terminal which forms one of the contacts of my improved switch.

I have provided an inverted cup shaped housing 14 which is fastened by screws 36 to the motor 10 above the terminal 11 and which is preferably pressed from relatively light sheet metal. A switch blade 15 is secured at one end in the rear portion of the housing 14 by means of a terminal bolt 16 and insulation 17. The insulation member 17 is of square section and extends through a correspondingly squared opening in the housing to thereby be non-rotatably secured. A portion of the bolt 16 adjacent to its head is also squared at 18 and extends through correspondingly squared openings in the blade 15 and insulation 17.

It may thus be seen that the blade 15 is prevented from rotating around the bolt 16 independently of the clamping force of the bolt. A sheet of insulating paper 19 is fastened in the housing 14 by engagement with the bolt 16, and extends within the top and side portions of the housing. Thus, if the blade 15 should be displaced to one side of the housing due to the failure of the insulation 17 or for other reasons it still may not become short circuited against the metal walls of the housing.

The blade is assembled in the housing by

inserting the bolt 16 through the openings in the blade 15, insulating paper 19, and insulating washers 17. The bolt is then inserted in the housing 10 and a nut 20 screwed down on this bolt to secure the members rigidly together. A cable 21 extends from the car battery and is provided with a conventional terminal 22 secured to the free end thereof, this terminal being fastened onto the bolt 16 by means of a lock nut 23.

The free end of the blade 15 is disposed directly over the head so that it may be flexed downwardly into contact with this head to complete the electrical circuit therebetween. Means are provided for flexing this blade which consists of a coupling 24, operating rod 26, and equalizing link 30. The coupling 24 is reciprocally mounted in a suitable opening 25 formed in the upper portion of the housing 14 and the rod 26 is threaded into the upper end of this coupling and extends in a diagonal direction up through the floor boards of the car, these boards being illustrated by dotted lines 27. A head 28 is formed on the upper end of the rod 26 in position to be conveniently depressed by the driver of the car.

The lower end of the coupling 24 is provided with an axial bore 31 into which the link 30 is loosely fitted. This link is preferably stamped from a sheet of fibre but, if desired, it may be turned or formed by other means from any insulation material. The lower end of the coupling 24 is flanged outwardly to form a stop whereby the upward movement of the coupling will be limited.

The free end of the blade 15 extends forwardly from the bolt 16 and is bent back upon itself at 29 wherein an opening 37 is provided to receive a detent 32 formed on the lower end of the link 30. That portion of the link adjacent to the detent 32 is enlarged so that it may co-act with the bent portion 29. It may thus be seen that when the rod 26 is depressed, it forces the link 30 downwardly which brings the blade 15 into contact with the head 13 to complete the electrical circuit. It will be noted that the blade 15 is flexible and that the free end bends in an arcuate path around the bolt 16 while the coupling 24 reciprocates in a straight path through the opening 25. The function of the link 30 is to convert the reciprocating movement of the coupling into an arcuate path so that there will be no sliding action between the parts.

Referring to Figure 3, I have shown the shape normally assumed by the blade 15 when removed from the housing 14 by the dotted lines 35. It will be seen that this blade is bowed upwardly at 38, adjacent to the section clamped by the bolt 16, and that the outer end is bent downwardly at 39 intermediate of its ends. When the blade is assembled in the housing it is deflected into

the position shown by solid lines 33 by the link 30 so that rattle between the parts is entirely eliminated and so that the blade will at all times be resiliently held in its inoperative position.

As the head 28 is depressed the blade 15 first assumes the position, shown by dotted lines 34, where an initial contact is made by the extreme forward end of the blade with the terminal head 11. A further depression of the head 28 forces the end of the bent portion 29 into contact with that portion of the blade adjacent to the bowed portion 39 so that the blade is flattened into full contact with the terminal head 11. This fully engaged position is illustrated in Figure 4. It may be seen that as the blade is thus flattened its point of initial contact or extreme forward end is forced to slide a short distance along the terminal head. This sliding action is very desirable as it tends to remove any pitting scale from the points of initial contact.

When the head 28 is released, the center portion of the blade first pulls away from the terminal head and assumes the position shown at 34, and then the extreme forward end is drawn away. The arcing which results when the current is broken always takes place at the forward end of the blade and, as this end is kept clean by the above described sliding action, a flow of current is always assured when the switch is operated. The main portion of the contacts always remain clean because the arcing is restricted to the forward portion of the contacts.

Among the many advantages arising from the use of my improved device, it perhaps should be repeated that I have provided a switch in which the arc produced when the switch is broken is restricted to a relatively small area over which a limited sliding action occurs to thereby prevent pitting of the switch contacts. I have thus obtained the desirable features of the sliding knife type switch together with the simplicity of construction of the push type switch.

Some changes may be made in the arrangement, construction, and combination of the various parts of my improved device without departing from the spirit of my invention, and it is my intention to cover by my claims, such changes as may reasonably be included within the scope thereof.

I claim as my invention:

1. In a switch, a terminal, a switch blade having one end fixedly anchored and the other end arranged to arcuately flex into contact with said terminal, a reciprocating operating means, and a link disposed between the operating means and the free end of said blade whereby sliding action between the blade and link and operating means, due to the variance between said reciprocating and arcuate movements, is eliminated.

2. In a switch, a terminal, a switch blade

having one end fixedly anchored and the other end arranged to arcuately flex into contact with said terminal, a reciprocating operating means, and a link of insulating material disposed between said operating means and the free end of said blade whereby sliding action between the blade and link and operating means, due to the variance between said reciprocating and arcuate movements, will be

10 eliminated.

3. In a switch, a terminal, a switch blade having one end fixedly anchored and the other end arranged to arcuately flex into contact with said terminal, an operating rod 15 mounted to reciprocate axially, one end thereof being adjacent to the free end of said blade, a coupling secured to said adjacent end having an axial bore therein, and a link loosely mounted in said bore and projecting therefrom to the free end of said blade, whereby sliding action between the blade and link and coupling, due to the variance between said reciprocating and arcuate movements, will be

20 eliminated.

25 4. In a switch, a terminal, a switch blade having one end fixedly anchored and the other end arranged to arcuately flex into contact with said terminal, an operating rod mounted to reciprocate axially into contact with said terminal, one end thereof being adjacent to the free end of said blade, a coupling secured to said adjacent end having an axial bore therein, a link of insulating material loosely mounted in said bore and projecting therefrom to the free end of said blade, whereby sliding action between the blade and link and coupling, due to the variance between said reciprocating and arcuate movements, will be

35 eliminated.

40 5. In a switch, a terminal, a switch blade having one end fixedly anchored and the other end arranged to arcuately flex into contact with said terminal, an axially reciprocating operating means having one end adjacent to the free end of said blade, said adjacent end having an axial bore therein, a link of insulating material loosely mounted in said bore and projecting therefrom to the free end of said blade, whereby sliding action between the blade and link and operating means, due to the variance between said reciprocating and arcuate movements, will be

45 eliminated.

50 6. In a switch, a terminal, a switch blade arranged to arcuately flex into contact with said terminal, an axially reciprocating operating rod extending diagonally from the free end of said blade and in the plane of said flexing movement, and an insulating link disposed between said rod and free end of said blade, whereby the diagonal reciprocating movement of the operating rod will arcuately flex the switch blade while sliding action between these parts is eliminated.

65 7. In a switch, a terminal, a switch blade

arranged to arcuately flex into contact with said terminal, the free end thereof having an opening therein, an axially reciprocating operating rod extending diagonally from the free end of said blade and in the plane of said flexing movement, a coupling disposed on the end of said rod adjacent to the switch blade, said coupling having an axial bore therein aligned with the opening in said blade, and an insulating link extending into said opening and bore and loosely mounted in each, whereby the diagonal reciprocating movement of the operating rod will arcuately flex the switch blade while sliding action between these parts is eliminated.

70 8. In a switch, a terminal, a bowed switch blade having one end fixedly anchored and the other end arranged to arcuately flex into contact with said terminal, and means for initially applying the free end of said blade into contact with a portion of said terminal, the further application of which applying means flattens the blade thereby increasing its effective length and producing a sliding action over the initial area of contact while enlarging the contact area to the full area of the terminal.

75 9. In a switch, a terminal, a bowed switch blade having one end fixedly anchored and the other end arranged to arcuately flex into contact with said terminal, an operating rod mounted to reciprocate axially, one end thereof being adjacent to the free end of said blade, a coupling secured to said adjacent end having an axial bore therein, and a link of insulating material loosely mounted in said bore and projecting therefrom to the free end of said blade, whereby initial actuation of said rod applies the free end of said blade into contact with a portion of said terminal and further application of the rod flattens the blade thereby increasing its effective length to produce a sliding action over the initial area of contact, said link compensating for the variance between the arcuate movement of the blade and the reciprocating movement of the rod to thereby uneffect the sliding action of the initial area of contact.

80 10. In a switch, an inverted cup-shaped housing, a switch blade, a bolt extending through suitable aligned openings in one end of said blade and housing and insulated from the latter, a terminal mounted to enter the open end of said housing in position whereby the blade may be arcuately flexed into contact with said terminal, an operating rod reciprocally mounted in the bottom of said housing adjacent to the free end of said blade, and a link disposed between the free end of said blade and said operating rod, said blade being so initially formed that it must be partially flexed when in its inoperative position, thereby preventing rattle between the blade and link and operating rod and housing.
